United States Patent Office.

M. H. GARDNER, OF NEW YORK, N. Y.

Letters Patent No. 78,079, dated May 19, 1868.

MACHINE FOR ENAMELLING PAPER.

The Schedule referred to in these Letters Patent and making part of the same.

TO ALL WHOM IT MAY CONCERN:

Be it known that I, M. H. GARDNER, of the city, county, and State of New York, have invented a new and useful Improvement in Machines for Enamelling Paper, applicable also to enamelling or coating other surfaces or material, of which the following is a full, clear, and exact description, reference being had to the accompanying drawing, forming part of this specification, and in which—

Figure 1 represents a longitudinal sectional elevation of a machine constructed in accordance with my improvement.

Figure 2 a plan of the same.

Figure 3 represents an inverted plan or under side view of a portion of an endless belt or apron, with its grippers, as used in the machine.

Figures 4 and 5, transverse sections thereof, taken as indicated by the lines $x x$ and $z z$ in fig. 3; and

Figure 6 a longitudinal view of the brush for laying on the enamel, detached.

Similar letters of reference indicate corresponding parts.

My improvement has for its object the production of a machine, more especially designed for the enamelling of paper, which, while embracing other important features, will serve automatically to lay and distribute the enamelling-mixture on to the paper in an even or regular manner, and to blend and smoothen the same over the surface as the paper or material is fed through and delivered from the machine in a continuous line or series of detached sheets.

My invention consists, firstly, in an enamel-mixing vessel or chamber, arranged over the tank or chamber which supplies a laying-on brush, and provided with a revolving mixing-brush, operating in connection with stationary brushes and a distributing-screen, that has its discharge preferably controlled by a valve or gate.

The invention also consists in the employment of a travelling endless belt or apron, for feeding the paper or material to be enamelled, and constructed with thickened sides or edges, for guiding the apron, and restraining it from irregular expansion or contraction in direction of its width; likewise in forming the belt or apron with spaces or openings in it, for dividing the belt into lengths corresponding to the lengths of the sheet being passed, and allowing of the surplus enamelling-mixture to escape through the belt, either section of which is provided at its edge with automatically-operating grippers, for holding and releasing the sheets.

The invention also consists in constructing the drums, which carry the endless belt or apron, with grooves at or near their one end, to receive the one thickened edge of the belt, in combination with adjustable or removable rings fitted over the drums, and serving as guides to the belt on its opposite side or edge, and to accommodate different widths of belt.

Furthermore, the invention consists in a peculiarly-constructed supply-trunk and cylinder, in combination with a laying-on brush rotating in the latter, and valves or cocks for regulating the supply of the enamelling-mixture from the trunk through the cylinder to the laying-on brush.

Likewise, the invention consists in a peculiar adjustable construction of the laying-on brush to accommodate different widths of paper, by attaching its longitudinal rows of bristles, or certain of them, to sliding bars, movable in direction of the length of the brush-stock.

Also, the invention embraces an angular arrangement of distributing or levelling-brush or brushes, adjustable to vary their width of action on the paper; also, in a combination with the same, or other equivalent device or devices, of a blending-brush or brushes, which may also be made adjustable to suit different widths of paper.

Referring to the accompanying drawing, A represents a mixing-chamber or vessel, preferably made detachable from the machine, to facilitate the putting in and removal or changing of the enamelling-material or composition, which is mixed and stirred or worked therein, to give to it the requisite clearness, consistency, and uniformity, by means of a revolving brush, B, acting in concert with stationary brushes, C, arranged on either side of the rotating brush in the lower half of its travel, and preferably combining with such devices a screen, D, below, to exclude the passage of any foreign or coarse matter, and gate or slide, E, to regulate the discharge of enamelling-mixture to a tank or chamber, F, and that serves to give a close bottom to the vessel A, when moving it to or from its position over the tank, or when otherwise necessary to stop the flow.

The tank or chamber F is provided, at or near its bottom, with one or more front outlets, a, that may, if desired, be controlled by a gate or gates, and that answers to pass off the enamelling-mixture into a trunk, G, constructed to partly surround the top and front of a horizontal cylinder, H, in which is located a revolving brush, I, that travels as indicated by the arrow y, and is supplied with enamelling-mixture from the trunk G in a nicely-adjustable manner, as regards feed, by or through a double row of intermediately-arranged faucets or screw stop-cocks, b, operating to cover or uncover orifices c in the periphery of the cylinder H. The mixture thus taken up by the brush I is delivered or laid on the paper through an oblong opening, d, in the cylinder H.

This brush I is of peculiar construction, to give to it an expanding character, to adapt it to work on paper of different widths, by arranging certain of the longitudinal rows of bristles, of which it is composed, on, or attaching them to sliding bars, e, made capable of adjustment along grooves f in the brush-stock or hub, said sliding bars being only of half or a portion of the length of the stock, while the other, or alternate rows, g, of bristles, that likewise extend only a portion of the stock, may be fixed or made to occupy a stationary relationship on or to the latter, so that, by shifting the brush-slides e, that may be in single or double sets between the stationary rows g of bristles, a varied length of operating-surface is given to the brush to suit different widths of paper.

The paper to be enamelled is laid or fed in detached sheets or strips on to an endless travelling-belt or apron, J, at the feed-end h of the machine, each sheet being clamped or held by fingers or grippers i, as the latter, or a weighted arm, j, connected with them, strike and travel under a fixed rail, k. This belt J is made up in sections or with open spaces, l, in it, for the surplus or escaping portion of the enamelling-mixture to pass off or through the belt into a trough or tank, K; which prevents waste. Each intervening or carrying portion of the belt, which may either be entire or of a slatted formation, has the fingers i arranged along its advance edge by a swinging rod, m, connected with the weighted arm j, that, on escaping from under the fixed rail k, after the sheet has passed through the machine, drops, to release hold on the sheet. Said belt may be made wholly or in part of rubber or leather, and is carried and driven by revolving end-drums, L, the one of which may be adjustable relatively to the other, to suit different lengths of belt or variations in its stretch, while it is guided and prevented from buckling or collapsing in a transverse direction by making its sides or edges, n, of a thickened formation, the thickened edge on the one side working in grooves, o, made in or round the drums L at or near their one end, and the other thickened edge being guided by the outer of a series of rings, M, slipped on or over a reduced portion of the body of the drum, and which afford a ready means, by slipping on or off certain of the rings, for working different widths of belt, according to the size of the paper to be enamelled.

The enamelling-mixture laid on the paper by the brush I is distributed or levelled, and streaks removed from its surface, as the paper travels forward, by causing it to pass under any desired number, arranged, say, side by side, of angularly-disposed distributing or levelling-brushes, N, formed by brush-bars jointed or pivoted as at r, and capable of being raised or lowered, to regulate the pressure of the brushes on the paper, also adjustable by or along a slotted bar, s, at their opposite ends, nearest to the revolving brush I, and where the bars are furthest apart, to accommodate the said brush or brushes N to different widths of paper being worked. In rear, again, of these brushes N are, or may be, any number of straight blending-brushes, P, located, say, one in rear of the other, and serving to soften or blend down the enamelled surface, and give to it a regular and even finish, immediately before the paper is released from gripe by the fingers which hold it on the belt, and which should continue to hold it till the paper or sheet is clear of the blending-brush or brushes.

These last-named brushes may be adjustable one in rear of the other, widthwise of the belt, in a somewhat similar manner to the arrangement described for expanding or contracting the operating surface of the brush I, to adapt them to different widths of paper.

A machine thus constructed will be found well suited to enamelling wall-paper, but is also applicable for enamelling or coating other paper or material.

What is here claimed, and desired to be secured by Letters Patent, is—

1. The arrangement, within the mixing-vessel or chamber A, of the revolving brush B and stationary brushes C C, for operation together, substantially as described.
2. The combination, with the revolving brush B and stationary brushes C C, of the mixing-vessel or chamber A, screen D, and slide or gate E, essentially as specified.
3. The travelling endless belt or apron J, constructed with thickened sides or edges n, and divided into sections by openings l, having fingers or grippers i, at or near their edges, as herein set forth.
4. The drums L, grooved at or near their one end, and provided with detachable rings M, in combination with the endless belt J, formed with thickened sides n, for operation together, as described.
5. The combination of the trunk G, cylinder H, provided with openings c and d, revolving brush I, and valves or faucets b.
6. The rotary brush I, constructed substantially as described, with its rows of bristles, or certain of them, attached to or carried by sliding bars of less length than the brush-stock, and adjustable along the same, to vary the width or length of the operating-surface of the brush, to adapt it to different widths of paper, as herein set forth.
7. The angularly-arranged brush or brushes N, adjustable as described, for operation on or over the surface of the paper or other material, essentially as and for the purpose or purposes herein set forth.
8. In combination with the distributing or levelling-brushes N, the blending-brush or brushes P, for action together, as specified.

M. H. GARDNER.
